UNITED STATES PATENT OFFICE.

GEORGE C. FLOWER, OF PITTSBURGH, PENNSYLVANIA.

DIE.

1,310,068.

Specification of Letters Patent. Patented July 15, 1919.

Application filed October 9, 1918. Serial No. 257,438.

To all whom it may concern:

Be it known that I, GEORGE C. FLOWER, a citizen of the United States, residing at Pittsburgh, in the county of Allegheny and 5 State of Pennsylvania, have invented certain new and useful Improvements in Dies, of which the following is a specification.

My invention consists of an improvement in dies, particularly adapted to the manufacture of connecting arms, girts, or braces 10 made of flattened pipe metal or other blanks.

It has for its object to provide die mechanism adapted to shear off the corners of a swaged blank, and to also punch a bolt hole 15 therein, whereby to provide finished ends for the flattened blank, in the manner more fully hereinafter described.

In the drawings, showing one preferred embodiment of the invention,

20 Figure 1 is a perspective view of one end of a brace or girt rod showing the end thereof in swaged down form previous to operation by the dies;

25 Fig. 2 is a similar view showing the end of the girt, after the shearing and punching operations;

30 Fig. 3 is a longitudinal central vertical sectional view through an apparatus utilizing my invention, showing the blank in position after being sheared and punched;

Fig. 4 is a plan view thereof; and

Fig. 5 is a transverse sectional view on the line V—V of Fig. 3.

In the manufacture of braces and girts for 35 the purpose of bracing any desired structure, as for instance, an oil well or other derrick, the girts are commonly made of pipe sections, swaged down flat at each end and bolted to the main corner or other frame-work by a bolt extending through the central terminal portion of the brace or girt. Ordinarily, the swaging operation leaves the end of the blank in rectangular form, more or less ragged and irregular, causing resulting 40 interference with the connected parts, unless removed or finished.

My invention has in view to provide means for removing the corner portions of the swaged down or flattened attaching terminals, and to also punch out a centrally arranged securing bolt hole, with a minimum 50 number of operations and with a view to speed and economy of operation.

In carrying out my invention, I provide a suitable frame or base 2 mounted upon a

supporting bed plate or base 3 and suitably secured thereto for rigid connection and operation. Mounted in the end portion of frame 2, either integrally therewith or separately, is a backing or supporting punching 60 die member 4 having a clearance opening 5 for the punched out waste metal in forming the central bolt hole 6. Inwardly in front of the bearing face 7 of die 4 is a receiving space *a* bounded within back face 7 and side 65 walls 8, 8, against the inner faces of which walls the edge portions 9 of the swaged down blank 10 bear when the blank is inserted in space *a*.

A supporting bottom or limiting floor 11 70 is provided against which the end of the blank rests when inserted between wall faces 8, 8, as in Fig. 5, at each side of which are clearance openings 12, 12, for escape of the corner portions in the blank, as sheared. In 75 front and at each side of cavity *a* are shearing edges 13, 13, rounded or shaped to the desired shape of the sheared end of the blank, whereby to provide an approximately rounded end for the blank when sheared. 80

A reciprocable die 14, mounted between the side portions 15, 15, of frame 2 and corresponding in contour to the edges 13, operates therewith by means of actuating cams 16, 16, of power driven shaft 17, mounted in 85 suitable bearings 18, 18. Die 14 is retracted by any suitable spring mechanism 19 and operates, when blank 10 is inserted in cavity *a*, to shear off the corner portions which fall downwardly through clearance openings 12. 90

An independent punching die 20 mounted within a receiving cavity 21 of die 14 and connected with operating spindle 22 having an enlarged head 23, is also normally retracted by spring 24 within die 14. Punch 95 20, after the shearing operation, is projected forwardly of die 14 by means of suitably formed and timed cam 25 operable shortly after the shearing operation, both cams permitting retraction of the shearing die and 100 punching die, whereby to provide for withdrawal of the finished blank and insertion of another one.

The construction and operation of the invention will be readily understood and appreciated from the foregoing description. It provides substantially simultaneous 105 means for shearing and punching the blank in one operation, or two quickly succeeding operations. The size, proportions and other 110

features of the invention may be readily changed or varied by the skilled mechanic to suit varying sizes and shape of blanks, but all such changes are to be considered as within the scope of the following claims.

I claim:—

1. Mechanism for shearing and punching a flattened blank comprising a bottom support and a fixed die provided with positively arranged shearing edges and clearance openings for waste material at each end of said support, and a composite die having co-acting shearing edges and a punch, and means for actuating said die and punch.
- 10 2. Mechanism for shearing and punching a flattened blank comprising a bottom support and a fixed die provided with positively arranged shearing edges and clearance openings for waste material at each end of said support, a reciprocable die having co-acting shearing edges, a punch in said die, and means for reciprocably actuating said die and punch.
- 15 3. Mechanism for shearing and punching a flattened blank comprising a bottom support and a fixed die provided with positively arranged shearing edges and clearance openings for waste material at each side of said support, a reciprocable die having co-acting shearing edges, a punch in said die, means for actuating said shearing die, and independently operative means for actuating the punch.
- 20 4. In combination, a frame having a bottom support, a receiving recess for a flattened blank and lateral shearing edges and clearance openings for waste at each side of said support, a punching die beyond said shearing edges, a reciprocable shear mounted in the frame and co-operable with said shearing edges, a punch mounted in the shear, and
- 25
- 30
- 35
- 40

cam mechanism for actuating the shear and punch.

5. In combination, a frame having a bottom support, a receiving recess for a flattened blank and lateral shearing edges and clearance openings for waste at each side of said support, a punching die beyond said shearing edges, a reciprocable shear mounted in the frame and co-operable with said shearing edges, a punch mounted in the shear, cam mechanism for actuating the shear and punch, and means for retracting the shear and punch.

6. In combination, a frame having a bottom support, a receiving recess for a flattened blank and lateral shearing edges and clearance openings for waste at each side of said support, a punching die beyond said shearing edges, a reciprocable shear mounted in the frame and co-operable with said shearing edges, a punch mounted in the shear, cam mechanism for actuating the shear, and cam mechanism for actuating the punch subsequent to the shear actuation.

7. In combination, a frame having a supporting bottom, a receiving recess for a flattened blank and lateral shearing edges and clearance openings for waste at each side of said support, a punching die beyond said shearing edges, a reciprocable shear mounted in the frame and co-operable with said shearing edges, a punch mounted in the shear, cam mechanism for actuating the shear, cam mechanism for actuating the punch subsequent to the shear actuation, and spring mechanism for retracting the shear and punch.

In testimony whereof I hereunto affix my signature.

GEORGE C. FLOWER.
